Patented Aug. 4, 1964

198,783

RECLINING CHAIR FOR VEHICLES

Chester J. Barecki, 901 Broadway Ave. NW,
Grand Rapids, Mich.

Filed Dec. 31, 1962, Ser. No. 73,004

Term of patent 14 years

(Cl. D15—8)

Fig. 2

FIGURE 1 is a front perspective view of a reclining chair for a vehicle embodying my new design; and

FIGURE 2 is a rear perspective view thereof.

The end of the chair not shown is of conventional configuration. The dotted line showings are for illustrative purposes only.

I claim:

The ornamental design for a reclining chair for a vehicle, substantially as shown and described.
